London, England

Application January 8, 1938, Serial No. 184,064
In Great Britain January 11, 1937

4 Claims. (Cl. 188—78)

This invention relates to brake-applying means of the kind in which a shoe or shoes are moved into contact with the drum by mechanism comprising a pair of elongated link members arranged obliquely end to end and operatively connected with actuating means which move the two co-operating ends simultaneously in a transverse direction in the manner of a toggle, the outer extremities of the link members being thereby caused to have a spreading action and apply the brake.

The invention has for its object to provide an improved construction of brake-applying means which is very simple to manufacture and which has been found to possess a very good operating efficiency, the friction losses being comparatively small. The invention is accordingly characterised by the fact that the link members in a brake-applying device of the kind above referred to abut end to end and roll one against the other during the application of the brake.

Thus, the invention provides a brake-applying means of the above kind in which each of the link members has a curved surface at each end, the arrangement being such that one of said surfaces rolls upon the other link member during the application of the brake, and the other curved surface of the first-mentioned link member simultaneously rolls upon the end of the brake shoe or an intermediate member adapted to actuate a shoe. Preferably the cooperating rolling surfaces on the link member and on the brake shoe or plunger are shaped so that a given movement of the actuating means produces a constant movement of the brake shoe or plunger throughout the whole range of movement of the applying means.

Two examples of brake-applying means according to the invention are illustrated in the accompanying drawings in which

40 Figure 1 is a side elevation of a device adapted for mechanical and fluid pressure actuation;

Figure 2 is a vertical longitudinal central section of Figure 1 with parts in elevation;

Figure 3 is a front elevation of a modified construction as arranged for mechanical actuation;

Figure 4 is a sectional plan taken on the line 4—4 of Figure 3;

Figure 5 shows in plan view a modified form of link member arranged for use in the applying means in Figures 4 and 5; and

Figure 6 is a fragmentary diagrammatic side elevation showing to an enlarged scale a method of locating the link members.

A housing 10 which is substantially T-shaped, 55 as will be seen in Figure 2, is mounted upon the

usual back-plate 11 of the brake by means of studs 12 carrying nuts 13 and spring washers 14. It will be seen that the hole 15 in the back-plate is extended in a direction circumferentially of the brake so as to allow the housing 10 to "float" 5 and take up its own position of equilibrium when the brake is applied. The transverse limb 16 of the housing 10 is formed throughout its length with a square channel 17, the mouth of which is closed by a removable cover 18 secured by studs 10 and nuts 19, so as to form a passageway.

Two plunger members 20 and 21 are mounted slidably in the respective ends of the passageway 17, and each is grooved as indicated at 22 for engagement with the web portion of the corresponding brake shoe (not shown). The inner parts of the plungers 20 and 21 are formed with deep grooves 23 and 24 respectively which serve to accommodate a pair of flat link members indicated at 25 and 26. At their outer ends these are 20 formed each with a curved end surface 27 which is adapted to roll upon the bottom 28 of the corresponding groove 23 or 24. The outer end of each link member 25 and 26 has concentric side surfaces 29 which serve to locate the link 25 member within the passage 17 and allow it to move angularly without creating undue side play.

At its inner end each of the link members 25 and 26 is also formed with a rounded surface indicated at 30, and these are adapted to roll together with a view to providing an extremely efficient brake-applying action. For moving the link members 25 and 26 an actuating head 31 is arranged to move transversely across the centre part of the passageway 17, and is grooved at 32 35 for receiving the members 25 and 26. The latter are fitted respectively with pivot pins 33 and 34 which pass into the actuating head 31, said head being notched as indicated at 35 for the accommodation of the pin 33 so as to ensure that any 40 endwise thrust on the link members 25 and 26 is transmitted by them directly and is not imposed upon the pivot pins 33 and 34.

For moving the head 31 the latter is formed with a stem 36 which is screw-threaded at its 45 outer end and carries a nut 37 and a bifurcated fitment 38 which is adapted to be connected mechanically with the usual hand brake lever (not shown), principally for the purpose of allowing the brake to be applied in emergency or during 50 parking.

Liquid pressure is normally used for actuating the brake, and this is fed through a connection 39 into a cylinder 40 formed in that part of the housing passing through the back-plate 11. A 55

collar 41 having a tubular stem 42 surrounding the stem 36 constitutes the fixed end wall of the working space, and is provided with a U-shaped annular cup 44 to prevent leakage of liquid.

5 The cylinder 40 is also fitted with an annular piston 45 which has a U-shaped cup 46, and which bears at its outer end upon the nut 37 so that when liquid under pressure is forced into the cylinder 40 the stem 36 is moved so as to apply the brake. The return movement of the piston 45 and the actuating head 31 is effected by the usual pull off springs (not shown) associated with the brake shoes, a relatively weak coiled compression spring 47 within the cylinder 40 serving merely to hold the packing cups 44 and 46 in position. Excessive movement of the piston 45 is prevented by a spring ring 48, while a flexible boot 49 serves to exclude water and grit in the usual manner. A bleeding plug 50 is provided at the highest part of the cylinder 20 40 for allowing air to be abstracted during the process of filling the system with working liquid.

It is, of course, well known to spread apart a pair of brake shoes by means of a simple toggle mechanism comprising for example a pair of links which are both connected by a pin joint to an actuating member, their outer ends being attached respectively also by pin joints to the shoes of the brake. This arrangement, however, 25 is found to be unsatisfactory in practice as the mechanical advantage or "leverage" which is obtained varies considerably during the operative range of the parts. Moreover, the whole of the circumferential braking force imparted by 30 or to the shoes is imposed on the three pin joints, and has the effect of creating excessive friction as well as accelerating the wear of the moving parts. This defect is to all intents and purposes quite overcome by the invention, since the compression force exerted between the plunger members 20 and 21 is transferred by the relatively robust rolling surfaces 27 and 28 to the link members 25 and 26, and these in turn are in direct rolling contact at the curved surfaces 30. 35

40 The only friction which is created upon the pins 33 and 34 is that due to the brake-applying tension in the stem 36. It will further be appreciated that the elongated nature of the link members 25 and 26 reduces the angular movement of the links relative to the applying head 31 to a very small amount, and this again considerably reduces the frictional loss.

In this embodiment the bottoms 28 of the grooves 23 and 24 are disposed truly radially with 55 regard to the axis of the plungers 20 and 21, and the curved surfaces 27 at the outer ends of the link members are, therefore, shaped so as to produce a substantially uniform mechanical advantage throughout their range of movement. 60 A close approximation which is satisfactory in practice can be obtained by making the surfaces 27 so that they are arcuate and are struck from the centre, which is indicated at 51 in Figure 2. In this figure the link members 25 and 26 occupy 65 a position at the middle of their possible travel, and it will be seen that with this disposition of the parts the centre 51 lies upon the axis of the passageway 17. The variation produced in the mechanical advantage is very slight, and this can, of course, be corrected by slightly modifying the shape of the curved surfaces 27.

A modified construction of shoe-spreading device is shown in Figures 3 and 4. The back-plate 11 carries a substantially T-shaped housing 10, 70 in the transverse limb 16 of which two slotted

plunger members 20 and 21 are slidably mounted. At its outer end each of these plungers is formed with a depression 52, and these are engaged by thrust members 53 and 54 respectively cooperating with the web portions of the adjacent brake 5 shoes indicated at 55 and 56. As will be more clearly seen in Figure 3 the thrust member 53 comprises a pair of screw-threaded parts, and this member can thus be extended in length by rotating an adjusting disc 57, thus regulating the 10 working clearance of the brake shoes 55 and 56.

A stem 36 serves as the actuating means for the brake and is slidably mounted, the working parts being protected from moisture and dirt by a rubber boot 49. At its extremity the stem 36 is formed with a knob 58 which is seated in the base of a groove 32 formed in an actuating head 31 as before. The plungers 20 and 21 are also formed with grooves 23 and 24 respectively, and these accommodate a pair of link members indicated at 59 and 60. These are of the form shown in Figure 4, and are mounted within the actuating head 31 by a pair of loosely fitting pins 33 and 34 so that the adjacent curved surfaces 30 can roll upon one another and thus relieve 25 the pins 33 and 34 from the main braking force. At their outer ends the link members 59 and 60 have curved surfaces 61 and 62 respectively which are concentric with the pins 33 and 34 and which roll upon obliquely disposed cam surfaces 30 63 and 64 constituting the bottoms of the grooves in the plungers 20 and 21. Thus, as tension is applied to the stem 36 the inner ends of the link members 59 and 60 are drawn towards the back-plate 11, thus causing their outer end surfaces 35 61 and 62 to roll upon the surfaces 63 and 64 and consequently spreading apart the brake shoes 55 and 56. As before, floating movement of the housing 10 can be permitted by providing clearance spaces in the back-plate as indicated at 65. 40 A thin metal plate 66 conveniently serves to close the front end of the opening occupied by the actuating head, and a resilient finger 67 formed integrally with said plate cooperates with teeth on the periphery of the disc 57 to preserve the 45 setting of the latter.

If desired, the manufacture of the link members 59 and 60 can be somewhat simplified by utilising a tubular bush 68 as the curved rolling surface 30 at the inner end of the link member, 50 as will be seen in Figure 5.

In the construction of brake-applying means illustrated in Figure 6, the link members have curved rolling surfaces 27 at their outer ends formed similarly to those in Figures 1 and 2, but 55 an alternative method is employed for locating the link members. As before, each link member 25 and 26 cooperates with a surface 28 upon a corresponding plunger member, such as that shown at 20, but these plunger members have a 60 tooth 70 which mates with a corresponding space 71 formed in the link member. The link members are moved in the direction of the arrow 72 by an actuating head 31 which engages loosely with pivot pins 33 and 34 so that owing to the formation of the surfaces 27 the plunger members are spread apart. In the meantime the surface 73 of the tooth space 71 engages with the tooth 70, 65 thus preventing the link members from slipping. By making the tooth 70 of involute form having 70 its pitch line coincident with the surface 28, and by shaping the tooth space 71 correspondingly, a pure rolling action can be obtained between the tooth 70 and the surface 73 of the space 71. This surface 73 is, of course, an involute and its 75

curvature is obtained according to the usual method for gear teeth, taking the curved surface 27 as the pitch line. Thus, with this form of link member there is rolling between the surfaces 36, 5 the surfaces 27 and 28, and between the tooth 79 and the surface 73 of the tooth space 71 the only rubbing friction occurring at pins 33 and 34 on account of the applying force.

What I claim is:

1. In a vehicle wheel brake, a toggle link mechanism for spreading apart a pair of brake shoes, comprising a housing, a pair of elongated thrust links within the housing arranged end to end, curved surfaces on the inner ends of the thrust links in contact with one another, actuating means extending through the housing which displace the inner ends of the thrust links in a direction substantially at right angles to the direction of thrust, curved surfaces on the outer ends of the thrust links and a pair of plungers slidable within the housing, at opposite sides thereof, with which the curved outer end surfaces of the thrust links coact, the contact made at both ends of the links during the application 20 of the brake being of a substantially wholly rolling nature.

2. In a vehicle wheel brake, a toggle link mechanism for actuating a pair of brake shoes, comprising a housing, a pair of elongated toggle links within the housing for applying thrust to spread apart the shoes, a curved surface on the inner end of each link, a curved surface on the outer end of each link concentric with the surface on the inner end, means extending through the housing for applying movement to the inner ends of the links in a direction at right angles to the direction of thrust, and a pair of plungers associated with the brake shoes and slidable within the housing at opposite sides thereof, which plungers have inclined surfaces in contact with the curved outer ends of the links, the contact at

both ends of the links being of a purely rolling nature.

3. In a vehicle wheel brake, toggle means for spreading a pair of brake shoes into contact with a brake drum, comprising a housing, a pair of elongated thrust links arranged end to end within the housing, actuating means extending through the housing for moving the inner ends of the links in a direction at right angles to the direction of thrust, circular bearing bushes at the inner ends of the links and in contact with one another, curved surfaces at the outer ends of the link members, and intermediate plunger members slidable in the housing at opposite sides thereof which transmit the thrust from the links to the brake shoes and have inclined bearing surfaces which make contact with the outer ends of the links, the action between the bushes at the inner ends of the links and between the outer ends of the links and the plunger members being of a wholly rolling nature during the application 20 of the brake.

4. In a vehicle wheel brake, a toggle mechanism for spreading apart a pair of brake shoes into contact with a brake drum, comprising a housing, a pair of elongated thrust links arranged end to end within the housing, actuating means extending through the housing for moving the inner ends of the links in a direction substantially at right angles to the direction of thrust 30 in the links, curved surfaces at the inner ends of the links in contact with one another, a toothed surface at the outer end of each link, a plunger member adjacent the outer end of each link and slidable within the housing to operate the brake 35 shoes, and a toothed surface on the plunger member which coacts with the toothed surface at the outer end of the corresponding link member, a wholly rolling action taking place at the ends of the link members when the brake shoes 40 are being spread apart.

FRANK GORDON PARNELL.
